UNITED STATES PATENT OFFICE.

FELIX RUAU, OF LYNCHBURG, VIRGINIA, ASSIGNOR TO UNITED CIGARETTE MACHINE CO., INC., OF LYNCHBURG, VIRGINIA, A CORPORATION OF VIRGINIA.

CIGARETTE-CUT-OFF MECHANISM AND METHOD.

Application filed March 27, 1922. Serial No. 546,985.

This invention relates to a cut-off mechanism and method for use in continuous rod cigarette machines; and has special reference to the provision of a novel method for cutting the continuous cigarette rod into units of cigarette length and to the mechanism employed in the practice of the method.

The cut-off mechanisms now universally employed in continuous rod cigarette machines consist of a rotating cutter device having a compound reciprocating and oscillating motion on the machine and operative for cutting the rod into sections or units of cigarette length. As is well known, the productive capacity or output of a continuous rod cigarette machine depends very largely upon the speed and accuracy of operation of the cut-off mechanism in severing the rod into cigarette lengths, the difficulty in cigarette machines of this type having been the provision of a cut-off mechanism capable of operation at very high speeds and capable of withstanding the strain and wear and tear due to the rapid reciprocating and oscillating movement of the cutter elements. A principal object of my present invention comprehends the provision of a novel cut-off mechanism capable of high speed and ease of operation whereby the capacity or output of the cigarette machine may be considerably increased.

In prior machines of this type, the reciprocating and oscillating cut-off mechanisms function to sever the continuous rod into the cigarette lengths or units, the cutting being effectuated in one step. By my present invention I propose to effect the cutting of the rod in two steps, the continuous rod being first severed into small rods of multiple cigarette lengths, these small rods being then cut or divided in cigarette sections or units. This I accomplish by employing two cutter devices for effecting the two cutting steps. A principal object of my present invention may therefore be said to comprise the provision of a cut-off mechanism and a method for cutting the continuous cigarette rod into cigarette lengths in which, in conjunction with the cutter device now employed, a second cutter device is utilized, the first or primary cutter functioning for dividing the continuous rods into smaller rods having lengths which are multiples of the length of the cigarette, the second or secondary cutter functioning for dividing

or cutting the said small rods into the final cigarette sections or lengths. By first cutting the continuous rods into rods of multiple cigarette lengths I am enabled to operate the first or primary cutter at a much lower reciprocating and oscillating rate, with a given speed of rod movement, or conversely, I am enabled to obtain or permit of a greater speed of rod movement and consequently a greater output of the cigarette machine with a given speed or rate of operation of the cut-off mechanism.

Another principal object of my present invention relates to the provision of a simplified and improved primary cut-off device in which the moving parts are reduced in number and the arrangement otherwise simplified, a primary cut-off mechanism capable of great speed of operation being thereby obtained.

To the accomplishment of the foregoing and such other objects as may hereinafter appear, my invention consists in the elements and their relation one to the other, as hereinafter particularly described and sought to be defined in the claims, reference being had to the accompanying drawings which show preferred embodiments of my invention and in which:

Figure 1 is an elevational view with parts broken away of my cut-off mechanism showing the primary and secondary cut-off devices,

Figure 2 is a cross sectional view of the same taken on the line 2—2, Figure 1 and showing the construction of the primary cut-off mechanism,

Figure 3 is a cross sectional view taken on the line 3—3, Figure 1 and showing the construction of the secondary cut-off mechanism and associated parts,

Figure 4 is an enlarged fragmentary view of parts shown in Figure 3,

Figures 5 and 6 are vertical and side elevational views of a modified secondary cut-off mechanism, and

Figures 7 and 8 are views showing a still further modification of the secondary cut-off mechanism.

As heretofore pointed out, the method I employ for cutting the continuous rod into cigarette lengths consists in first cutting the rod into small rods of lengths equal to a multiple of the cigarette length by means of a primary cut-off mechanism and in there-

2
after dividing or cutting the said small rods into cigarette sections or lengths by means of a secondary cut-off mechanism. Referring now to the drawings, the apparatus I 5 employ in the practice of the method consists generically in the primary cut-off mechanism P and the secondary cut-off mechanism S associated therewith.

The primary cut-off mechanism P of my 10 invention is of the type now employed in cigarette machines in which a rotatable cutter or blade is reciprocated longitudinally of the cigarette machine for movement during cutting activity in the direction of and 15 at the same speed as the moving continuous rod and in which the cutter is oscillated transversely of the machine into and out of the path of movement of the rod for cutting the same. The primary cutter of my invention, however, for a given production or output 20 of the machine, is operated at a lesser cyclic speed than prior cut-off mechanisms, operation of the primary cut-off mechanism at higher cyclic speeds permitting a correspondingly greater product on or output 25 of the cigarette machine. The primary cut-off mechanism of my present invention has been further improved to the end of reducing the number of moving parts of the same 30 and otherwise simplifying the construction thereof for the purpose of obtaining a device capable of standing up at the desired high speed of operation. Referring now more in detail to the drawings, I provide the rotatable cutter c having the compound reciprocating and oscillating motion referred to, the said cutter in the present exemplification of my invention being preferably attached to a tubular element or sleeve 10 freely 35 slidable and rotatable on a cutter shaft 11. For reciprocating the cutter c there is provided a carriage 12 slidable or reciprocable on spaced shafts 13 and 14, the shaft 14 being fixed in opposed bearings 15 and 16 respectively, preferably formed integral with the framework casting 17 of the machine, the shaft 13 being preferably supported in the bearing bracket 18, also preferably integral with the framework casting 17, the 40 shaft 18 extending only partially across the cut-off mechanism, as will be clear from a consideration of Figure 1 of the drawings. The carriage 12 is provided with the usual guide or ledger tubes 19 and 20 for receiving 45 and guiding the continuous cigarette rod, the ledger tubes being movable with the carriage as is usual in these devices. The carriage 12 is further provided with the spaced arcuate plates 21 and 22, these plates 21 and 50 22 engaging therebetween the wheel 23 fixed to or forming part of the cutter sleeve or tube 10. With this construction it will be apparent that upon reciprocation of the carriage 12 on the shafts 13 and 14 the cutter c will be reciprocated in opposite directions 55

by the engagement of the wheel 23 between the carriage plates 21 and 22. The cutter shaft 11 with this construction, as will appear further presently, is mounted independent of the carriage and is not reciprocable therewith, and with this construction it will be seen that the only reciprocating parts comprise the carriage having a small mass, the ledger or guide tubes carried thereby and the cutter c with its attached sleeve 10, the reciprocating parts being thus reduced to a minimum with the consequent reduction of the factors of mass and inertia.

For effecting oscillation of the cutter c the cutter shaft 11 is journaled in the apertured bosses 24 and 25 formed at the ends of the arms 26 and 27 of the actuating levers 28 and 29, the said levers 28 and 29 being fulcrumed on the machine as by being rotatable on a shaft 30 journaled in the upstanding spaced brackets 31 and 32 attached in any desired manner to the framework of the machine. The shaft 30 is in effect a rock shaft, the levers 28 and 29 being rockable or oscillatable on said shaft for effecting the oscillation of the cutter c, the arms 33 and 34 of the levers 28 and 29 comprising the actuating arms for effecting the desired oscillations. During the oscillation of the cutter c the wheel 23 thereof is movable between the arcuate plates 21 and 22, the said arcuate plates therefore confining the said wheel for reciprocating the same in any position of the cutter during its oscillation. For rotating the cutter c there is provided the usual sheave 35 attached to the said cutter, the said sheave being rotatable by means to be described hereinafter during the oscillation and reciprocation of the cutter c.

For effecting the reciprocation of the carriage 12 and its associated parts, there is provided the drum cam 36 fixed to a shaft 37 journaled in the spaced depending bracket bearings 38 and 39 attached to the machine framework, the said cam 36 being provided with the operating cam groove 40 and cooperating with the cam groove there is provided the lever 41 rockable or oscillatable on a shaft 42 journaled in the opposed bearings 43 and 44 attached in any suitable manner to the framework 45 of the machine, the lever 41 being preferably provided with an elongated sleeve-like shank 46 rockable on the shaft 42 for obtaining a well balanced and smooth operation. The lever 41 is provided with the opposed arms 47 and 48, the arm 47 being provided at its end with a freely rotatable cam follower 49 movable in the cam groove 40, the arm 48 of the lever being connected to the carriage 12 for reciprocating the same. The connection between the lever arm 48 and the carriage 12 may comprise a slidable block 50 freely movable in a way or channel 51 provided in the carriage 12. For the purpose of varying the

throw or travel of the carriage 12 to obtain varying lengths of cigarettes the connection between the lever arm 48 and the carriage 12 is preferably made adjustable and to this end the block 50 may be adjusted in the arm 48, the said arm being provided with an elongated recess or slot 52, the said block 50 being adjustable longitudinally of the slot and being fixed in any adjusted position as by means of the securing means 53. Fixed to the cam shaft 37 there is provided the gear 54 meshing with a gear 55 attached to a drive shaft 56. With this construction it will be seen that upon rotation of the drive shaft the cam 36 will be rotated to effect the reciprocation of the carriage 12 and its associated parts, the carriage being movable in the direction of and at the same speed as the continuous cigarette rod *r*, which is guided- ly fed through the ledger tubes 19 and 20.

For effecting the oscillation of the cutter *c* during the reciprocating movements thereof, the levers 28 and 29 are oscillated preferably from the cam shaft 37. To this end the cam shaft 37 is provided at its opposite ends with the eccentric pins or studs 57 and 58 receiving the eccentric strap portions 59 and 60 preferably formed integrally with actuating arms 61 and 62, the arms 61 and 62 being secured in position on the eccentric pins or studs 57 and 58 as by the securing means 63 and 64 respectively. The arms 61 and 62 are pivotally connected to the ends of the operating lever arms 33 and 34 of the levers 28 and 29 and for the purpose of adjusting the position of the cutter *c* with respect to the moving rod *r* the connection between these parts is preferably made adjustable. To these ends the arms 61 and 62 are provided at their upper ends with the apertured bosses 65 and 66, in which is journaled the transverse shaft 67, the said shaft being adjustable in elongated recesses such as 68 in the lever arm 33 shown in Figure 2 of the drawings, the parts being secured in any adjusted position with any suitable securing means. With the provision of this construction it will be obvious that upon rotation of the cam shaft 37 the arms 61 and 62 will be actuated for oscillating the lever arms 28 and 29 for in turn effecting the desired oscillation of the cutter *c*.

For rotating the cutter or blade *c* during its compound movement, the sheave 35 of the cutter is rotated by means of a belt 69 movable over an opposed pulley or sheave 70 fixed to a shaft 71, the latter rotatable in the bearings 72 and 73 provided in an upstanding bracket 74 attached in any desired manner to the framework of the machine, the said shaft 71 receiving motion from a drive shaft such as 75 as by means of the belt 76 trained or movable over a drum or pulley 77 on the drive shaft 75 and an opposed drum or pulley 78 fixed to the shaft 71.

In the operation of the primary cut-off mechanism *P* the cutter *c* is given a compound rotating, reciprocating and oscillating motion, the cyclic speed of the cutter, that is the number of oscillations and reciprocations per unit of time of the said cutter being such as to effect the cutting of the continuous rod *r* into smaller rods of multiple cigarette lengths. The lengths of the small rods cut may, for example, be 2, 3 or 4 times the normal length of a cigarette, and in the present exemplification of my invention I have shown the cutter *c* effective for cutting the continuous rod into rods having lengths equivalent or equal to twice the normal length of a cigarette. With this construction it will be seen that with a given output of a cigarette machine the cyclic speed of the moving parts may be decreased, subjecting the same to relatively small strains and negligible wear and tear. It will be further seen that where higher cyclic speeds are desired the cut-off mechanism *P* may take care of or handle a longer rod in a given time, the output or productive capacity of the machine being considerably enhanced thereby, the construction of the cut-off mechanism having been further so designed as to permit of very high cyclic and rectilinear speeds.

After the small rods are cut by the primary cut-off mechanism the rods are conveyed to a secondary cutter *S* and then cut into final cigarette sections or lengths. The secondary cutter *S* comprises, generically, the stationarily mounted and rotatable cutter *c'* and the advancing or feeding means *f* for conveying the small rods to the rotatable cutter to be cut thereby. The feeding mechanism *f* and the cutter *c'* are supported on the side plates 79 and 80 which are, in turn, supported by and attached to the bracketed framework 81 of the machine. The cigarette rods, after being cut by the primary cut-off mechanism, are fed through a U-shaped channel 82 supported by the side plate 80, the rods being moved in position to be rapidly fed forward by a rotatable feed wheel 83 having an active portion 84 and a mutilated or nonactive portion 85, the said wheel 83 being preferably surfaced with a band of rubber for frictionally contacting or engaging the small rods such as *r'* fed through the channel 82. The peripheral speed of the wheel 83 which is rotated in the direction as shown by the arrow in Figure 1 of the drawings, is preferably greater than the rectilinear speed of the cigarette rod *r*, the cut cigarette rods *r'* being thereby quickly advanced from the channel 82 to the feed mechanism to be presently described. Rotatably mounted in the side plates 79 and 80 there is provided the shaft 86, and on the said shaft are attached in any desired manner a plurality of spaced notched

disks 87, 88, 89 and 90 comprising a conveyer, the said notched disks being intended for receiving the cigarette rods r' and for feeding the same for cutting purposes. 5 Each disk 87 to 90 inclusive is provided with a plurality of spaced notches n and adjacent each notch there is provided a cigarette rod engaging finger such as f' . The cigarette rods r' when fed from the channel 82 are 10 passed between the spaced outer and inner guides 91 and 92 respectively, the said guides being arranged relatively to the notched disks 87 to 90 inclusive for guiding the cigarette rods r' into the notches n of the said 15 disks during the rotation of the disks in the direction as shown by the arrows in Figure 4 of the drawings, the manner of guiding the rods into the notches being clearly shown in Figures 3 and 4 of the drawings. The 20 notched disks 87 to 90 are given a continuous motion, the fingers f' of the notches functioning during the rotation of the disk in engaging successive rods r' and moving the same between the outer and inner guides 25 91 and 92, the parts being associated to make the successive cigarette rods take the successive positions as shown in Figure 4 of the drawings, the cigarette rods after completely entering the notches in the disks being then 30 ready for the cutting step. For the purpose of alining or registering the successive cigarette rods r' so that such rods may all be cut in exactly the same position, there may be further provided the side guides 93 and 35 94, the guide 94 being contoured to move the cigarette rods into registered and abutting position against the side guide 93.

In the rotation of the notched disk conveyer the cigarette rods are brought under 40 the influence of the rotatable cutter c' . The cutter c' is rotatably mounted in an arm 95 which is pivotally mounted for adjustment on a shaft 96 journalled in the side plate 80, as will be clear from a consideration of 45 Figures 1 and 3 of the drawings, the arm 95 being locked in adjusted position as by means of the securing elements 97. To assure the exact cutting of the cigarette rods the knife or cutter c' is arranged to contact 50 with one of the central notched disks such as 88, this disk being preferably made of hardened steel and serving as a ledger plate. In the present exemplification of my invention I show a single cutter c' for dividing 55 the cigarette rods of double length into the cigarette lengths, but it will be apparent that where the primary cut-off mechanism P produces rods of longer lengths a plurality of cutters c' may be provided for obtaining 60 the final cigarette sections or lengths.

After the cigarette rods r' are divided or 65 cut into the cigarette units the cigarettes are guided by means of the outer guides 91 and are deposited upon an endless receiver or conveyer 98 movable over drums 99 and

100 journalled in the framework of the machine, the drum 100 being preferably adjustable as by being journalled in blocks 101 70 slidable in ways or guides 102 in the framework of the machine and fixed in adjusted position as by means of the set screw device 103, this to the end of maintaining the receiver or conveyer 98 in properly taut condition.

The various parts of the secondary cut-off mechanism S are operated from the drive shafts 56 and 75 by means of the following provisions. For rotating the cutter or plate c' the cutter shaft is provided with a pulley or sheave 104 receiving an endless belt 105, the belt receiving motion from a pulley or sheave 106 fixed to the shaft 71, the belt 105 being guided by means of the spaced guide rollers 107 and 108. The shaft 71, as hereinbefore pointed out, receives motion from the drive shaft 75 and thus the cutter c' is actuated or operated from this drive shaft. The notched disk conveyer is operated by rotation of the shaft 86, this shaft being provided with a gear 109 meshing with a gear 110 fixed to the shaft 111, the said gear 110 in turn meshing with a pinion 112 on a shaft 113, the said shaft 113 being provided at an end opposed to the pinion end thereof with a sprocket wheel 114 over which is trained a sprocket chain 115 receiving motion from an opposed sprocket 116 fixed to the drive shaft 56. For operating the friction feed wheel 83 the said feed wheel is fixed to a shaft 117 journalled in a bearing 118 attached to the framework of the machine (see Figure 3), the shaft 117 carrying a sprocket wheel 119 over which is trained a chain 120 receiving motion from a sprocket wheel 121 attached to a shaft 122, the said shaft being journalled in a bracket 123, the shaft, in turn, receiving motion from the shaft 113 as by means of the intermeshing gears 124 and 125 fixed respectively to the shafts 122 and 113. The 105 sprocket chain 120 may be guided by means of the guide rollers 126 and 127, the said guide rollers being adjustably mounted in a bracket 128. For moving the endless receiver or conveyer 98 the drum 99 may be 110 positively actuated and to this end the said drum is attached to the shaft 111 carrying the gear wheel 110. With this construction it will be apparent that the notched disk conveyer, the endless conveyer 98 and the friction feed wheel 83, are all synchronously 115 operated from the drive shaft 56.

The secondary cut-off mechanism S for cutting the small rods into final cigarette lengths may be varied within wide limits, 120 Figures 5 to 8 of the drawings showing two modifications of this secondary cut-off mechanism. Referring to Figures 5 and 6 of the drawings, the cigarette rods r' of multiple cigarette lengths when fed through the 125

- U-shaped channel 82' fall or are deposited in the box or chute 129, the cigarette rods collecting in the said chute as shown in Figure 6 of the drawings. These cigarette rods 5 r' become arranged lengthwise in the grooves 130 of a carrier or conveyer wheel 131, the latter fixed for rotation on a shaft 132 and movable in the direction as shown by the arrow in Figure 6 of the drawings.
- 10 For limiting the passage of the cigarettes a roller 133 may be provided and for effectively keeping the cigarettes in the box 129 I may provide the fork 134 provided with the bifurcations 135 and 136 received by 15 the grooves 137 and 138 of the roller 133, the roller 133 being rotatable in the direction as shown by the arrow in Figure 6 of the drawings for limiting the movement of the cigarette rods r' in the chute or box 20 129. The cigarette rods r' in their movement on the carrier wheel 131, come between the guides 139 and 140 and are moved into registering position by means of the side guides 141 and 142. After the cigarette 25 rods r' are properly registered and positioned they are moved over the rotatable and preferably stationarily mounted cutter c^2 fixed to a shaft 143 and rotatable in bearing 144 of the arm 145, the said cutter moving in a groove 145' of the wheel 131 severing the double length rods r' into cigarette 30 units after which the cigarettes are deposited upon the endless conveyer or carrier belt 146 movable over the drum 147.
- 35 With this construction the secondary feeding devices and also the secondary cutter may be continuously operated in a manner similar to the continuous operation of the secondary cut-off mechanism shown in Figures 1 to 4 of the drawings, an unlimited speed of this secondary cutter being permitted thereby.
- Referring now to Figures 7 and 8 of the drawings, which show side and end elevational views of a third modification of the 40 secondary cut-off mechanism, the cigarette rods r' , after being cut by the primary cut-off mechanism, are moved through a U-shaped channel 148, the advanced cigarette rods r' being moved through this channel by the succeeding cigarette rods. The cigarette rods r' in being moved through the channel 148 in the direction shown by the arrow in Figure 7, are moved beneath a rotating brush 149 fixed to and rotatable with a shaft 150, the said brush 149 continuously rotating in the direction as shown by the arrows in Figures 7 and 8, the said brush having a peripheral speed greater than the linear speed of the moving cigarette rods r' coming from the primary cut-off mechanism. When the cigarette rods r' come under the influence of the rotatable brush 149 the said rods are more rapidly advanced in the channel 148 and are moved through ledger 45 tubes 151 and 152, the tube 152 being attached to or formed with the channel 148 and the tube 151 being attached to an extension of the said channel such as to a channel 153. For cutting the cigarette rods 70 r' there is provided a rotatable cutter c^3 freely rotatable on a shaft 154, the said shaft being journaled in an arm 155 of a rock lever 156, the other arm 157 of the said rock lever being provided with a cam follower 75 158 movable over a rotatable cam 159 fixed to a shaft 160, the said cam 159 being adapted to be rotated in the direction as shown by the arrow in Figure 8 of the drawings. The cutter c^3 by the provision of this construction is given a combined rotating and oscillating motion, the said cutter being adapted for intermittently moving into and out of the path of movement of the cigarette rods r' for cutting the same, the cam 80 159 and the lever 156 effecting the desired oscillating movement of the said cutter. During the cutting activity the motion or movement of the cigarette rods r' is checked so that cutting takes place with the rods 85 stationary. For checking the movement of the cigarette rods there is provided a movable stop 161 movable between the guide channel 153 and a guide channel 162, the said stop 161 comprising a plate preferably forming part of the rock lever 163 rockable on a shaft 164, the arm 165 of the said lever being provided with a roller or cam follower 166 movable over the cam surface of a cam 167 attached to the rotatable shaft 90 160. In the rotation of the shaft 160 with this construction it will be obvious that the stop 161 is moved into and out of the path of movement of the cigarette rods r' . Before the descent of the cutter c^3 for cutting the double rods r' , the stop member 161 is moved into the rod path by the cam 167 as shown in Figures 7 and 8, the motion of the cigarette rods advanced by the rotatable brush 149 being thus checked. The 95 110 brush 149, by its continued rotation, maintains the cigarette rods in exact position to be cut by the friction which the brush exerts upon the said rods. When positioned as shown in the drawings the cam 159 quickly moves the cutter c^3 against the ledger tube 151 and into the cigarette rod for effecting a clean and transverse cut therein. The construction and relative arrangement of the parts are such that after this operation takes place the stop 161 is quickly moved out of the path of rod movement and the cigarette lengths r^2 are advanced by the succeeding double rod r' into the channel 162 and beneath a second rotating brush 168 fixed to a shaft 169 continuously rotatable in the direction as shown by the arrow in the figure, the peripheral speed of the brush 168 being greater than the peripheral speed of the 100 115 120 first feeding brush 149, the cooperation 125 130

being such that the cigarette lengths or sections r^2 when moved beneath the brush 168 are rapidly fed forward out of contact with the succeeding rod r' and are deposited upon 5 the moving endless conveyer 170 movable over the drum 171. After the cut cigarette sections r^2 are moved by the brush 168 past the position of a stop 161 the said stop is again dipped or moved to descended position 10 for checking the motion of the succeeding rod r' to be cut.

The practice of my present method of cutting continuous cigarette rods into cigarette lengths or sections and the operation of the 15 cut-off mechanism employed in the practice of the method will, in the main, be apparent from the above detailed description thereof. In all the forms of my invention the continuous cigarette rod, after being formed by 20 the associated parts of the cigarette machine, is continuously moved through the cigarette guides 19 and 20 as is common in cigarette machines, a primary cut-off mechanism P having a compound reciprocating, oscillating and rotatable motion being employed for cutting the continuous cigarette rod r into small rods r' of multiple cigarette lengths, these small rods being then advanced or fed to a second cut-off mechanism S for cutting 25 the small rods into the final cigarette lengths or units. With the provision of this method and this cut-off mechanism it will be apparent that I am enabled to effect a cutting operation of the continuous rod at greater 30 speeds than in the universally employed cut-off mechanisms, the output or productive capacity of the machine being thereby considerably enhanced. It will be further apparent that with my improved primary cut-off mechanism a greater cyclic speed of operation is permitted, the movable reciprocating parts having been reduced to a minimum. It will be further seen that the parts are so 35 relatively arranged as to provide a compact, strong and durable machine capable of withstanding the rough use to which machines of this type are subjected in actual service.

While I have shown my device in the preferred form, it will be obvious that many 40 changes and modifications may be made in the structure disclosed without departing from the spirit of the invention, defined in the following claims.

I claim:

55 1. A cut-off mechanism for cigarette machines comprising a reciprocable carriage, an oscillatable cutter device associated therewith and reciprocated thereby, means for reciprocating the carriage and mechanism for oscillating the cutter device, the said mechanism being independent of said carriage, the construction being such that the cutter device only is reciprocated by movement of said carriage.

60 65 2. A cut-off mechanism for continuous rod

cigarette machines comprising a reciprocable carriage, a movable cutter associated therewith and reciprocated thereby, instrumentalities for reciprocating the carriage to move the same in the direction of rod movement and mechanism for moving the cutter across the path of movement of the rod, the said mechanism including a cutter shaft and means for moving the shaft, the said means and shaft being independent of said carriage.

3. A cut-off mechanism for cigarette machines comprising a reciprocable carriage, an oscillatable cutter associated therewith and reciprocated thereby, means for reciprocating the carriage and mechanism for oscillating the cutter, the said mechanism including a shaft carrying the cutter and lever means for oscillating the shaft, the said lever means being mounted independent of said carriage.

4. In a cut-off mechanism for continuous rod cigarette machines, a reciprocable carriage, a cutter shaft independent of said carriage, a cutter slideable on said shaft and associated with the carriage to be reciprocated thereby, instrumentalities for reciprocating the carriage to move the same in the direction of rod movement and mechanism for moving the cutter shaft to move the cutter thereon across the path of rod movement.

5. In a cut-off mechanism for continuous rod cigarette machines, a reciprocable carriage, a cutter shaft independent of said carriage, a cutter slideable on said shaft and associated with the carriage to be reciprocated thereby, instrumentalities for reciprocating the carriage and mechanism for oscillating the cutter shaft, the said mechanism including lever means having only an oscillating motion on the machine.

6. In a continuous rod cigarette machine, a cut-off mechanism comprising a carriage mounted for reciprocation on the machine framework, a cutter shaft mounted for oscillation on the machine framework and a cutter device slideable on said shaft and associated with the carriage to be reciprocated thereby.

7. In a continuous rod cigarette machine, a cut-off mechanism comprising a carriage mounted for reciprocation on the machine framework, a cutter shaft mounted for oscillation on the machine framework, a cutter device slideable on said shaft and associated with the carriage to be reciprocated thereby, instrumentalities for reciprocating the carriage and mechanism for oscillating the cutter shaft.

8. In a cut-off mechanism for cigarette machines, a reciprocable carriage, a movable cutter associated therewith and reciprocated thereby, means for reciprocating the said carriage and instrumentalities for moving the said cutter; the said means for reciprocating the carriage comprising a lever hav-

ing an operating arm adjustably connected to the said carriage for varying the length of travel thereof.

9. In a cut-off mechanism for cigarette machines, a cutter including a reciprocable carriage, means for reciprocating the said carriage comprising a lever oscillatable about an axis transverse to the path of movement of said carriage; the said lever being provided with opposed arms, a cam for actuating one of the arms and adjustable means connecting the other arm to the said carriage and adjustable for varying the length of travel of the said carriage.
10. In a continuous rod cigarette machine, a cut-off mechanism comprising a carriage mounted for reciprocation on the machine framework, a cutter shaft mounted for oscillation on the machine framework, a cutter device slideable on said shaft and associated with the carriage to be reciprocated thereby, instrumentalities for reciprocating the carriage and mechanism for oscillating the cutter shaft, the said mechanism comprising rockable or oscillatable levers and arms for 25 rocking the same and adjustable means connecting the arms and levers.
11. A cut-off mechanism for cigarette machines comprising a reciprocable carriage, an oscillatable cutter device associated therewith and reciprocated thereby, means for reciprocating the carriage, mechanism for oscillating the cutter device, the said mechanism being independent of said carriage, the construction being such that the cutter device only is reciprocated by movement of said carriage, the said means including a rock lever connected to the carriage, and a cam and cam shaft for operating the lever, the said mechanism including oscillatable 35 lever means and arms for operating the same actuated by said cam shaft.
12. In a continuous rod cigarette machine, a cut-off mechanism comprising a carriage mounted for reciprocation on the machine framework, a cutter shaft mounted for oscillation on the machine framework, a cutter device slideable on said shaft and associated with the carriage to be reciprocated thereby, instrumentalities for reciprocating the carriage and mechanism for oscillating the cutter device, the said mechanism comprising rockable or oscillatable levers and arms for 40 rocking the same and adjustable means connecting the arms and levers.

Signed at Lynchburg, in the county of Campbell and State of Virginia this 21st day of March A. D. 1922.

FELIX RUAU.
